CLAIM

The ornamental design for a sanitary countertop machine for storing and dispensing particulate ice, substantially as shown and described.

DESCRIPTION

FIG. 1 is a perspective view looking downward at the front, left side and top of a sanitary countertop machine for storing and dispensing particulate ice, showing my new design;

FIG. 2 is a front elevational view thereof;

FIG. 3 is a side elevational view of the right side thereof;

FIG. 4 is a side elevational view of the left side thereof;

FIG. 5 is a rear elevational view thereof; and

FIG. 6 is a top plan view thereof.

The bottom is substantially planar and unornamented.

FIG.1

FIG.2

FIG.3

FIG. 4

FIG. 5

FIG. 6
